Leidy G. Scholl, Lansdale, Pa.

Application September 28, 1956, Serial No. 43,135

Term of patent 14 years

(Cl. D86—10)

Fig. 1

The characteristic feature of the design resides in the configuration of the upstanding sides of the body portion of the brush.

I claim:

The ornamental design for a fingernail brush, as shown and described.
